CIGARETTE-PACKING MACHINE

Johannes Neff, Dresden, Germany, assignor to
 "Universelle" Cigarettenmaschinen-Fabrik
 J. C. Müller & Co., Dresden, Germany

Application May 1, 1931, Serial No. 534,267, and
 in Germany May 3, 1930

6 Claims. (Cl. 226—5)

My invention relates to cigarette-packing machines and more particularly to machines for packing groups of cigarettes. It is an object of my invention to improve a machine of the kind

5 described with a view to eliminating certain difficulties in the operation of the existing machines, as will be explained below.

To this end I provide as many supply hoppers as there are groups of cigarettes, the hoppers being 10 arranged along the machine in vertically stepped relation, means such as gripper chains for feeding the first group to a station and means for feeding the next group to the station and for entraining the two groups together being pro- 15 vided.

Obviously the machine may be designed for any number of groups and the means for feeding the groups along the machines are so designed and arranged with respect to each other that they will 20 entrain all the groups collected at a station to which the feeding means have supplied a fresh group.

It is another object of my invention to provide 25 means for arranging cigarettes of oblong (oval) section in an oblique position. To this end I provide guiding means having grooves resembling rifling and so arranged that the cigarettes when leaving the guiding means are arranged in a 30 position relative to each other resembling that of scales or tiles.

It has already been suggested to combine several groups of cigarettes, each including a given number of parallel cigarettes in juxtaposition, by superimposing the groups whereupon they are 35 placed in a case. Various means have been suggested for combining groups in this manner. The groups of cigarettes are delivered to a vertical stepped guiding track along which they are conveyed by pushers, grippers or the like at various 40 levels, until they are combined.

If the groups were supplied to the track in transverse direction, each group was taken from a separate supply hopper. However it is rather difficult to supply the cigarettes to the track 45 transversely, more particularly with respect to the timing of the transversely moving means to feeding means, which may also be pushers, grippers or the like, for moving the cigarettes along the track.

50 It has further been suggested to take the groups of cigarettes from hoppers arranged within the track itself. In this case the several groups were taken from a single hopper and the principal difficulty was to move the groups to various levels.

55 According to my invention, I provide a separate supply hopper of known type for each group of cigarettes. These hoppers are arranged in vertically stepped relation along the track and each group from the first hopper is fed by pushers, grippers or the like to a station to which a group

from the second hopper is fed by other means, which may also be pushers or grippers, and these means then entrain the first group together with the second group, and so on.

If cigarettes of oblong cross section are to be 65 handled, each supply hopper is equipped with the aforesaid rifled guiding means.

In the drawings affixed to this specification and forming part thereof a machine embodying my invention and provided with two supply hoppers 70 is illustrated diagrammatically by way of example.

In the drawings

Fig. 1 is an elevation,

Fig. 2 is a plan view of the machine,

Fig. 3 is a partly sectional perspective illustration 75 showing rifled guiding means,

Fig. 4 is a diagram showing the cigarettes of a group in horizontal and in the oblique position which is imparted to them by the guiding means,

Fig. 5 is a section on the line V—V, and

Fig. 6 is a section on the line VI—VI in Fig. 1.

Referring now to the drawings, the machine is equipped with a horizontal table supported on uprights G, and 1 and 13 are supply hoppers arranged along the table. Each supply hopper is subdivided by vertical partitions 13' as shown for the hopper 13 in Fig. 5, by which the cigarettes are arranged in vertical piles. 3 and 3' are guiding means allotted to the hoppers 1 and 13, respectively which, as shown in Fig. 3, have rifled 90 grooves. The number of grooves in each guiding means 3 and 3' is equal to the number of vertical piles of cigarettes between the vertical partitions 13', as shown in Fig. 5, so that each groove receives a cigarette from the corresponding vertical pile. 95

The horizontal row of cigarettes in the grooves of the guiding means 3 and 3' will be referred to as "a group". 2 is a pusher for pushing the lowest group of cigarettes in the hopper 1 onto the guiding means 3. 2' is a bar which is secured to the rear end of the pusher 2, 37 is a guide on the table of the machine in which the bar is mounted to slide, 4 is a lever which is pivoted to one of the uprights G at its lower end 5 and engages the bar with its slotted upper end, 6 is a roller on the lever, 7 is a cam plate on a shaft 25 which is mounted to rotate in one of the uprights G for imparting rocking motion to the lever 4, and 36 is a pull-back spring attached to the lever 4. The stroke of the pusher 2 is so determined that it moves the group 100 of cigarettes G' a considerable distance along the guiding means 3, as shown in Fig. 1, whereupon it returns to its initial position. The group G' is now engaged by feeding means which in the present instance include a pair of sprockets 11, a chain 110 9 on the sprockets, and grippers 8 on the chain. The grippers engage the group G' and feed them along the guiding means 3. While the cigarettes are fed along the guiding means the rifled grooves move them into the position shown in full lines in

115

120

125

Fig. 4 from the position shown in dotted lines, so that the cigarettes are arranged in oblique positions, resembling scales or tiles. At the rear of the guiding means 3 a track 10 is provided and 5 equipped with side flanges 10' for holding the cigarettes in position. The grippers 8 on the chain 9 feed the first group G' as far as a station x, Fig. 1.

Means are provided for feeding the next group 10 G² from the hopper 13 on a track 12 which is arranged above the track 10. 14 is a pusher for pushing the lowest group of cigarettes in the hopper 13 onto the track 12. The mechanism for operating this pusher is similar to the mechanism 15 for operating the pusher 2 and includes a rocking lever 4' pivoted at 5' in the second upright G, a bar 14', a guide 38, a roller 6', a cam plate 7' on a shaft 19 and a pull-back spring 36'.

3' is a guiding means similar to the means 3 20 which is allotted to the track 12 so that the cigarettes in group G² are arranged in the oblique position illustrated in Fig. 4. The pusher 14 moves the group G² into the position shown in Fig. 1, and is then retracted. The group G² is 25 now engaged by the second feeding mechanism which includes a chain 31 on a pair of sprockets, only one of which is illustrated, grippers 15 on the chain and guiding sheaves 16 and 17. The grippers 15 feed the group G² in the direction of 30 the arrow in Fig. 1 as far as the guiding sheaves 16 and 17 which move each gripper down so far that it enters the track 10. The two groups G' and G² are now superimposed and are moved to the packing station (not shown) together by the 35 gripper 15, as indicated in dotted lines in Fig. 1.

The shaft 19 on which the cam plate 7' is secured, is the main driving shaft and is equipped with fast and loose pulleys 18, Fig. 5. 20 is a bearing for the shaft 19 in the upright G at the 40 right in Fig. 5, and 21 is an upright at the side of the machine for supporting the outer end of the shaft 19. 22 is a sprocket on the shaft 19, 24 is a sprocket on the shaft 25 of the cam plate 7, and 23 is a chain connecting the two sprockets. 26 is a second sprocket on the shaft 19, 28 is a sprocket on the shaft 29 of the sprocket 20 for the second 45 gripper chain 31, and 27 is a chain connecting the sprockets 26 and 28. 32 is a third sprocket on the shaft 19, 34 is a sprocket on the shaft 35 of the first gripper chain 9, and 33 is a chain connecting the sprockets. The shafts 35 and 29 are mounted to rotate in suitable bearings on the table of the machine, as best seen in Fig. 2.

In order to prevent interference of the grippers 50 8 on the chain 9 with the hopper 13 when they move along the upper reach of the chain 9, they are hinged to the links of the chain as shown in Fig. 5.

I wish it to be understood that I do not desire 55 to be limited to the exact details of construction shown and described for obvious modifications will occur to a person skilled in the art.

In the claims affixed to this specification no 60 selection of any particular modification of the invention is intended to the exclusion of other modifications thereof and the right to subsequently make claim to any modification not covered by these claims is expressly reserved.

I claim:—

70 1. A machine for packing groups of cigarettes comprising a plurality of supply hoppers arranged in vertically stepped relation along the machine,

partitions in each hopper for arranging the cigarettes in vertical piles, means for feeding a group from the first hopper to a station, and means for feeding to said station a group from the second hopper, said latter feeding means being arranged to entrain the two groups together, and all feeding means being arranged in line with said hoppers and in the direction in which the cigarettes are delivered to them from the hoppers.

2. A machine for packing groups of cigarettes comprising a plurality of supply hoppers arranged in vertically stepped relation along the machine, partitions in each hopper for arranging the cigarettes in vertical piles, means for feeding a group from each preceding hopper to a station, and means for feeding to said station a group from the succeeding hopper, said latter feeding means being arranged to entrain all the groups collected at a station, and all feeding means being arranged in line with said hoppers and in the direction in which the cigarettes are delivered to them from the hoppers.

3. A machine for packing groups of cigarettes comprising a plurality of supply hoppers arranged in vertically stepped relation along the machine, partitions in each hopper for arranging the cigarettes in vertical piles, means for ejecting from each hopper the bottom group of cigarettes, means for feeding the group ejected from the first hopper to a station and means for feeding to said station the group ejected from the second hopper, said latter feeding means being arranged to entrain the two groups together, and all feeding means being arranged in line with said hoppers and in the direction in which the cigarettes are delivered to them from the hoppers.

4. A machine for packing groups of cigarettes of oblong cross section comprising a plurality of supply hoppers arranged in vertically stepped relation along the machine, guiding means allotted to each hopper for moving the cigarettes into oblique position, means for feeding a group from the first hopper to a station, and means for feeding to said station a group from the second hopper, said latter feeding means being arranged to entrain the two groups together.

5. A machine for packing groups of cigarettes of oblong cross section comprising a plurality of supply hoppers arranged in vertically stepped relation along the machine, guiding means having grooves resembling rifling allotted to each hopper and arranged to move the cigarettes into oblique position, means for feeding a group from the first hopper to a station, and means for feeding to said station a group from the second hopper, said latter feeding means being arranged to entrain the two groups together.

6. A machine for packing groups of cigarettes comprising a plurality of supply hoppers arranged in vertically stepped relation along the machine, partitions in each hopper for arranging the cigarettes in vertical piles, means for feeding a group from the first hopper to a station, and means for feeding to said station a group from the second hopper, said latter feeding means being arranged to entrain the two groups together, said guiding means having grooves arranged in line with the spaces between said partitions, and all feeding means being arranged in line with said hoppers and in the direction in which the cigarettes are delivered to them from the hoppers.

JOHANNES NEFF.
